Des. 241,777
Patented Oct. 5, 1976

241,777

MEAT SPACER TRAY

Richard L. Allman, Seymour, Ind., and Vernon E. Meurer,
Fullerton, Calif., assignors to Standard Oil Company,
Chicago, Ill.

Filed Dec. 19, 1974, Ser. No. 534,570

Term of patent 14 years

Int. Cl. D15—07

U.S. Cl. D15—89

FIG. 2

FIG. 1 is a reduced perspective view of a meat spacer tray showing our new design;

FIG. 2 is a fragmentary top plan view thereof;

FIG. 3 is a fragmentary top plan view thereof, shown broken away for ease of illustration; and

FIG. 4 is a front elevational view thereof, shown broken away for ease of illustration.

The undisclosed bottom is molded to follow the contours of the top.

We claim:

The ornamental design for a meat spacer tray, as shown.

FIG. 3

FIG. 4
